(57) **CLAIM**

The ornamental design for a heat pump conveying device, as shown and described.

DESCRIPTION

FIG. 1 is a perspective view of a heat pump conveying device; FIG. 2 is a perspective view of a heat pump conveying device with a pump in hidden lines;

FIG. 3 is a side plan view of a heat pump conveying device; FIG. 4 is a side plan view of a heat pump conveying device; FIG. 5 is a front plan view of a heat pump conveying device; FIG. 6 is a back plan view of a heat pump conveying device; FIG. 7 is a top plan view of a heat pump conveying device; and,

FIG. 8 is a bottom plan view of a heat pump conveying device. The broken line showing of a heat pump is included for the purpose of illustrating environment and forms no part of the claimed design.
